UNITED STATES PATENT OFFICE.

GABRIEL P. B. HOYT, OF NEW YORK, N. Y.

ENGINE CRANK-MOVEMENT.

1,205,895.

Specification of Letters Patent. Patented Nov. 21, 1916.

Application filed December 17, 1915. Serial No. 67,369.

To all whom it may concern:

Be it known that I, GABRIEL P. B. HOYT, a citizen of the United States, and a resident of the city of New York, Jamaica, 5 borough of Queens, in the county of Queens and State of New York, have invented a new and Improved Engine Crank-Movement, of which the following is a full, clear, and exact description.

10 The object of the invention is to provide a new and improved crank movement more especially designed for use on internal combustion engines of the two or four-cycle type, and arranged to insure a proper transmission of the developed power without jar or vibration to balance the engine and thus provide an easy running thereof.

15 In order to accomplish the desired result, use is made of two crank shafts geared together to run in opposite directions and each provided with a crank for each cylinder of the engine, and a yoke attached to the piston rod of each engine and provided with parallel guideways having bearings engaged by the two complementary cranks of the crank shafts.

20 A practical embodiment of the invention is represented in the accompanying drawings forming a part of this specification, in which similar characters of reference indicate corresponding parts in all the views.

25 Figure 1 is a cross section of the crank movement as applied to a two-cycle internal combustion engine, the section being on the line 1—1 of Fig. 2; Fig. 2 is a sectional side elevation of the same on the line 2—2 of Fig. 1; Fig. 3 is a reduced side elevation of the same and showing more particularly the crank movement applied to two end cylinders of an engine having a number of pairs of cylinders; Fig. 4 is an enlarged cross section of one of the yokes provided with bearings engaged by the complementary cranks of the two crank shafts; and Fig. 5 is a cross section of the crank movement as applied to an internal combustion engine of the four-cycle type.

30 The engine crank movement illustrated in Figs. 1, 2, 3 and 4 is applied to an internal combustion engine of the two-cycle type having pairs of cylinders 10, 11 mounted on a suitable frame or base 12. In

the cylinders 10 and 11 of each pair of cylinders reciprocate pistons 13, 14 connected by piston rods 15, 16 with yokes 17, 18, 55 alike in construction, so that it suffices to describe but one in detail. Each yoke 17, 18 is provided with two parallel guideways 20, 21, in which are mounted to slide bearings 22, 23 engaged by the crank pins 24, 60 25 of cranks 26, 27 forming part of crank shafts 28, 29 journaled in suitable bearings arranged on the main frame or base 12.

65 The crank shaft 28 is the power-driven shaft and is provided at one end with a fly wheel 30, and the crank shaft 29 is a counterbalance shaft and is provided with a fly wheel 31 at the side of the engine opposite the one on which the fly wheel 30 is located, as will be readily understood by reference 70 to Fig. 3. The guideways 20 and 21 of each yoke 17 and 18 extend transversely, that is, at a right angle to the axes of the shafts 28, 29, and the complementary cranks 26, 27 are so arranged one relatively to the other 75 that the bearings 22, 23 slide in opposite directions in their guideways 20 and 21. The shafts 28 and 29 are connected with each other by gear wheels 32 and 33 to cause the shafts to rotate in unison when 80 the engine is running.

85 It is understood that the cranks 26 and likewise the cranks 27 are arranged at angles one relatively to the other on the corresponding crank shaft 28 or 29, so that the power of the explosive agent is transmitted to the shaft 28 in the proper sequence according to the number of cylinders of the engine. It is expressly understood that each yoke has two parallel guideways 20 and 21 90 in which reciprocate the bearings 22, 23 in opposite directions during the running of the engine. The crank movement shown and described is preferably inclosed in a double casing 40 as indicated in Figs. 1 95 and 5.

100 The crank movement shown in Fig. 5 is the same as above described but is shown applied to the piston rod 50 of a piston 51 mounted to reciprocate in the cylinder 52 of an internal combustion engine of the four-cycle type.

105 Each yoke 17 or 18 has its guideway 20 formed of top and bottom plates 60, 61 en-

gaging at their ends screw rods 62, 64 provided with nuts 64, 65, of which the nuts 64 engage the top of the plate 60 while the nuts 65 engage the bottom of the plate 61, the 5 two plates 60 and 61 being held spaced apart by spacing sleeves 66, 67 through which extend the corresponding portions of the rods 62, 63. The lower guideway 21 is likewise formed of two plates 70, 71 held on 10 the lower ends of the rods 62, 63 by the use of nuts 72, 73 screwing on the screw rods, and the plates 70 and 71 are held spaced apart by sleeves 74, 75 engaging the screw rods 62, 63. The piston rod 15 (16) is 15 screwed or otherwise secured to the uppermost plate 60 of the guideway 20, and the two guideways 20 and 21 are held adjustable on the two rods 62, 63 to space the same the desired distance apart and to space the individual plates 60, 61 and 70, 71 apart to insure proper sliding movement of the bearings 22 and 23. When the engine is running the power developed in the cylinders 10 and 11 is transmitted by the pistons 13, 14 to 20 the yokes 17, 18 which by their bearings 22, 23 engaging the pins 24, 25 of the cranks 26, 27 cause a rotary motion of the shafts 28, 29, and as the latter are geared together and the bearings 22, 23 travel in opposite 25 directions it is evident that the shafts 28 and 29 rotate in opposite directions. As the shafts carry fly wheels at their opposite ends a complete counterbalancing of the engine is had to insure an easy running of the 30 engine.

Having thus described my invention, I claim as new and desire to secure by Letters Patent:

1. A crank movement, comprising parallel 40 shafts provided with cranks, gear wheels connecting the said shafts with each other to run the shafts in opposite directions, and a yoke having parallel guideways extending in a plane at right angles to a plane passing 45 through the axes of the said shafts, the said crank arms engaging the said guideways.

2. A crank movement, comprising parallel shafts provided with cranks, gear wheels connecting the said shafts with each other 50 to run the shafts in opposite directions, a yoke having parallel guideways extending in a plane at right angles to a plane passing through the axes of the said shafts, and bearings slidable in the said guideways and 55 engaged by the crank pins of the said cranks, the latter being arranged one relative to the other to slide the bearings alternately in opposite directions.

3. A crank movement for an engine, comprising a pair of crank shafts having their axes in a plane containing the axis of the engine cylinder, gear wheels connecting the said shafts with each other to run the shafts in unison and in opposite directions, and a

yoke adapted to be attached to an engine 65 piston and provided with two parallel guideways engaged by the cranks of the said crank shafts.

4. A crank movement for an engine, comprising a rod having a reciprocating movement in the direction of its axis, a yoke provided with two parallel guideways, each guideway having parallel guide plates, rods on which the ends of the said guide plates of both guideways are adjustably secured, the 70 said rod being attached to one of the outer guide plates, bearings slideable in the said guideways, and two parallel crank shafts 75 having their cranks engaging the said bearings, the cranks being arranged to slide the 80 bearings in opposite directions, gear wheels connecting the shafts with each other, and fly wheels on opposite ends of the said shafts.

5. A crank movement for a multicylinder 85 engine, comprising a power crank shaft having cranks, one for each cylinder, the cranks standing at an angle one to the other, a balancing crank shaft parallel to the said power crank shaft and having cranks complementary to the cranks on the power crank shaft, gear wheels connecting the said shafts with each other, and yokes adapted to be attached to the piston rods of the engine, each yoke having two parallel guideways 90 and slideable bearings in the said guideways and of which one is engaged by a crank shaft on the power crank shaft and the other bearing is engaged by the complementary 95 crank of the balance crank shaft.

6. A crank movement for a multicylinder 100 engine, comprising a power crank shaft having cranks, one for each cylinder, the cranks standing at an angle one to the other, a balancing crank shaft parallel to the said power crank shaft and having cranks complementary to the cranks on the power crank shaft, gear wheels connecting the said shafts with each other, and yokes adapted to be attached to the piston rods of the engine, 105 each yoke having two parallel guideways and slideable bearings in the said guideways and of which one is engaged by a crank shaft on the power crank shaft and the other bearing is engaged by the complementary 110 crank of the balance crank shaft, the said cranks engaging the bearings of a yoke being arranged to slide the bearings in opposite directions.

7. A crank movement for a multicylinder 115 engine, comprising a power crank shaft having cranks, one for each cylinder, the cranks standing at an angle one to the other, a balancing crank shaft parallel to the said power crank shaft and having cranks complementary to the cranks on the power crank shaft, gear wheels connecting the said shafts with each other, yokes adapted to be attached to

the piston rods of the engine, each yoke having two parallel guideways, slideable bearings in the said guideways and of which one is engaged by a crank shaft on the power 10
6 crank shaft and the other bearing is engaged by the complementary crank of the balance crank shaft, the said cranks engaging the bearings of a yoke being arranged to slide the bearings in opposite directions, and fly

wheels on the opposite ends of the said shafts:

In testimony whereof I have signed my name to this specification in the presence of two subscribing witnesses.

GABRIEL P. B. HOYT.
